GRINDING MILL

Ernst Gerasch, Magdeburg-Hopfengarten, Germany, assignor to Fried. Krupp Grusonwerk Aktiengesellschaft, Magdeburg-Buckau, Germany

Application February 23, 1933, Serial No. 658,158
In Germany March 1, 1932

3 Claims.

(Cl. 83—9)

My invention relates to grinding mills of the rotary drum and ball type for finely comminuting and pulverizing solid materials in bulk, primarily hard substances such as minerals of different descriptions including ore, coal, coke, etc., also metallurgical, chemical and ceramic products, cement clinker and the like—and more particularly to improvements in grinding mills of the type composed of a plurality of individual grinding compartments or chambers so arranged around a common axis, as shown for instance in U. S. Patent 1,290,178 to Hachter and U. S. Patent 1,646,532 to Goebels, that the weight of the material and the grinding balls are more uniformly and symmetrically distributed within the mill, viz. on both sides of the central axis of the mill and will in part counterbalance each other with the result that less power is required for the operation of the mill. I have observed in the course of my experimental work with multiple chamber mills of various types including those described in the U. S. patents mentioned above, that the outstanding advantage of saving power, which in some cases amounts to 30% power saved in revolving the mill (see U. S. Patent 1,290,178 page 1 lines 38-49), is counterbalanced by more than one serious disadvantage which include the facts that the output of the mill is impaired, viz. being smaller than the output of mills of equal size, the rotary drum of which is not subdivided into a plurality of grinding chambers but presents one single chamber, and that the temperature to which the material under treatment rises in passing through the mill is higher than with mills of the single chamber type, an objectionable effect for instance in grinding explosives, food stuffs etc.

I have attempted to trace the cause of these drawbacks, by taking photos of multiple chamber mills while working, the front walls of the chambers were made from wire net work or glass, through which the movement of the grinding elements could be observed in all the different phases of the circular movement of the grinding chambers.

As the result of my investigations I attribute the said drawbacks to the fact that the pieces of material to be ground are not appropriately hit by the falling grinding balls, viz. not in the most effective manner at right angles perpendicularly from above, but under an angle of impact or descent considerably smaller than 90°, with the result that the impact force of the falling grinding balls is not fully used for the comminution of the material, but that a component of the impact

force is consumed by an undesired motion of the material which laterally recedes under frictional contact with the supporting walls, whereby heat is produced.

I have also found that the balls tend to obstruct the passage of the material entering the grinding chambers, thus impairing the working capacity of the mill, and that these drawbacks are the more noticeable the lighter the specific weight of the particular substance to be ground is in comparison to that of the material of which the grinding balls consist; in many cases—as known to practitioners—the balls and the linings of the drum must be made of a special material, different from iron, and chosen according to the nature, viz. the physical and chemical properties of the substance to be ground, and also in accordance to the respective purpose for which the pulverized substance is intended, for instance manufacture of paints or of explosives, photographic, medicinal goods, food stuffs etc.

One of the primary objects of the invention is to overcome the said drawbacks by providing a grinding mill of the type set forth and of improved construction, the intake of the grinding chambers being so designed that the material to be ground will easily find its way into the mass of balls and underneath the latter.

In connection therewith the invention aims at so re-designing the grinding chambers that a uniform and speedy progress of the material to be ground through the latter and a greater output of the mill is obtained.

Another object of the invention is to provide an improved mill of simple and sturdy construction the interior of the grinding chambers of which is readily accessible for supervision and repair, exchange of worn grinding balls, replacing of linings etc.

The nature and scope of the invention are briefly outlined in the appended claims and will be more fully understood by the following specification taken together with the accompanying drawing in which

Fig. 1 is a longitudinal section through a mill designed according to this invention and being shown by way of an example,

Fig. 2 is a cross section on line I—I of Fig. 1,
Fig. 3 is a cross section on line II—II of Fig. 1,
Fig. 4 is a cross section on line III—III of Fig. 1,

Fig. 5 is a cross section through the ball section of the mill drawn in a larger scale and elucidating the motion of the grinding balls in

the different compartments of the mill during their circular movement.

In the embodiment of the invention shown by way of an example the ball mill, identified as a whole by letter B, comprises a drum 10 rotatably mounted in bearings 11, 12 of frame 13 by means of hollow trunnions 14, 15—and being rotated by an electric motor 16 and a toothed gearing 17.

10 The interior of the drum 10 is subdivided by partition walls 20 (Fig. 4) into a plurality of individual grinding chambers which are arranged around the central axis of the drum at the distance therefrom. The said partition walls 20 are plane and deviate from the radial direction so as to enclose with their central portion c (Fig. 1) a hollow space hereinafter called "feed chamber".

Conveying means of appropriate design are provided at the front end of the mill B for charging the material to be ground into said feed chamber and thence into the grinding chambers. Perforated screens, serving as intake means are provided in the central walls c allowing the material to freely enter the grinding chambers and to find its way into the mass of grinding balls and underneath the latter, as will be seen hereinafter.

Protecting means are provided in the grinding chambers for keeping the grinding balls out of contact with the perforated screens, thus insuring an unobstructed flow of the material through the latter and preventing their becoming choked.

35 In the embodiment of the invention, shown by way of an example in the drawing, the said protecting means comprise a hood structure formed with partition walls a and a' which enclose the perforated screen i from above and at its inner side, and leave a free passage for the material entering the grinding chambers; I prefer to provide in addition in said passage a grate u, the bars of which are at a distance from each other which is smaller than the diameter of the balls or other gravitally controlled grinding elements 40 used in the mill; in this manner the intake screen i is rendered safe against injurious attacks from the balls and against being choked by the latter, and the material under treatment.

Manholes closed up by detachable lids 30 are provided in the outer walls of the grinding chambers so as to render accessible the interior of the latter for inspection and repair, exchange of worn balls for new ones, replacing of worn linings inside the mill etc.

55 In the embodiment of my invention shown by way of an example at the feed end of the ball mill B another grinding mill A having a drum 10' and gravitally controlled rods 40 as grinding elements is arranged in structural and cooperative union with the ball section B of the mill; the rods 40 are carried on and held together in bunches by systems of spokes 41, 41' which extend tangentially to a central hole 42 in the spoke structure of circular shape and form substantially triangular cages. As seen in the lower right (southeast by south) corner of Fig. 2 the rods 40 will periodically form a particularly high pile and bear against each other and the drum 10' with increased pressure, when lying in a certain wedge shaped portion of their triangular cages viz. that which presents the smallest angle.

By arranging said spokes 41, 41' in the specific tangential position described above and shown in Fig. 2 a very powerful comminuting effect is 75 obtained from the rods 40,—which is particularly

useful for rapidly breaking up hard materials composed of coarse granular pieces.

The material to be ground, after having been broken up in the rod section A of the mill, passes through a perforated disk 45 into a receiver R, provided as a storage member between the sections A and B, and thence through openings 35' of a partition wall 35 onto substantially radially extending vanes or chutes 36 which are provided in the space between said partition wall 35 and 10 the front walls of the grinding chambers; on sliding down from the chutes 36 the material to be reground in the ball section B of the mill arrives at a central chute member 36' wherefrom it slides into the feed chamber of the ball mill 15 described above.

The feed chamber is closed up at its rear end by a partition wall 38 (Fig. 1).

The re-ground material passes out of the ball mill B through a sieve plate 55 provided at the 20 rear end of the grinding chambers and is discharged by radial chutes 55' into the hollow trunnion 15.

Both trunnions 14, 15 are provided at their inner faces with helical ribs used as conveying 25 elements and being known per se.

Various changes and modifications in the design of grinding mills of my improved construction having the features described above may suggest themselves to practitioners in this field, 30 without departing from the spirit and the salient ideas of this invention and sacrificing any advantages obtained thereby.

For instance different intake and protecting means may be used in the ball section B of the 35 mill:

Good results as regards fineness of the pulverized product and output of the mill per unit of power consumed have been obtained with a combined rod and ball mill for reducing hard cement clinker into powdered Portland cement: The drum of the mill was 2.2 meters in diameter, 40 14 meters its total length, the ball section was 5 meters long and was subsequently reconstructed according to this invention, viz. subdivided by 45 plane partition walls longitudinally extending through the drum and deviating from the radial direction: The output of the mill rose by 10%, while 29% less power was consumed and the temperature of the pulverulent product went 50 down from 118° centigrade to 108° centigrade after the re-construction.

In both cases, viz. before and after the reconstruction the fineness of the powdered product was the same as ascertained at the laboratory 55 of the Society of German Portland Cement Manufacturers by sieving the products under comparison through a sieve of 4900 meshes.

What I claim is:

1. A grinding mill comprising a rotary drum, 60 partition walls longitudinally extending therethrough and subdividing the drum into a plurality of grinding chambers, said partition walls being plane and deviating from the radial direction, so as to enclose an additional chamber 65 at the centre of the drum, and means cooperatively associated with said grinding chambers for feeding thereinto and discharging therefrom the material under treatment, said feeding means comprising partition walls, provided in said central chamber and subdividing the latter into a plurality of channels, perforated screens provided in the circumferential walls of said central chamber for communication of the said channels with the individual grinding chambers, and 70 75

gravitally controlled conveying means for conveying the material to be ground through said channels and screens into the grinding chambers.

2. A grinding mill comprising a rotary drum, 5 partition walls longitudinally extending therethrough and subdividing the drum into a plurality of grinding chambers, said partition walls being plane and deviating from the radial direction, so as to enclose an additional chamber 10 at the centre of the drum, and means cooperatively associated with said grinding chambers for feeding therewith and discharging therefrom the material under treatment, said feeding means comprising partition walls, provided in said central chamber and subdividing the latter into a plurality of channels, perforated screens provided 15 in the circumferential walls of said central chamber for communication of the said channels with

the individual grinding chambers, gravitally controlled conveying means for conveying the material to be ground through said channels and screens into the grinding chambers, and a hood structure within the latter enclosing said perforated screen and being adapted to safeguard the latter against being damaged.

3. In a grinding mill a rotary drum, partition walls subdividing said drum into a plurality of non-communicating, eccentrically located grinding chambers, said partition walls being substantially plane and crosswise intersecting each other at acute angles so as to jointly enclose a separate chamber at the center of the drum, and means for feeding into said grinding chambers and discharging therefrom the material under treatment.

ERNST GERASCH.
